IMPRESSION SEAL

Thomas B. Wilder, Aberdeen, N. C.

Application April 22, 1936, Serial No. 75,823

8 Claims. (Cl. 101—3)

This invention relates to an improvement in impression seals of the type employed by public officials, such as a notary public, for impressing papers with their official characters.

5. Seals of this character which have been employed heretofore have been rather bulky, heavy, and unsatisfactory for carrying in the pocket or on the person of the official using such seal.

The object of my invention is to provide a seal
10 of this character which will be light in weight,
compact, and suitable for carrying on the per-
son or in the pocket of an official having such
a seal without bulkiness or discomfort.

15. In carrying out this object the seal is constructed with a casing preferably of sheet metal and is provided with a mouth portion into which the papers may be inserted to receive the impression seal, and a handle is pivoted in such a way as to press the impression dies together.

20. through the medium of cam surfaces. This enables the seal to be compact and being constructed of sheet metal, it is light in weight.

I have illustrated a preferred embodiment of my invention together with modifications there-
25 of, in the accompanying drawing in which:

Fig. 1 is a top plan view of the seal;

Fig. 2 is an edge view thereof:

Fig. 3 is a longitudinal sectional view therethrough:

30 Fig. 4 is a similar view at right angles to Fig. 3; Fig. 5 is a longitudinal sectional view through a seal embodying a modified form of actuating device; and

Fig. 6 is a plan view of a further modification.

35 My seal comprises a relatively flat tubular casing, preferably formed of two parts, 1 and 2, which provide the top and bottom for the tubular casing and have flanges turned in opposite directions and overlapping to form the sides of the tubular casing as indicated at 3, these side flanges being preferably secured together as by

The tubular casing formed by the parts 1 and 2 has the flanges notched out to provide a mouth 5 at one end thereof through which the papers may be introduced to receive the impression thereon. Located within the mouth 5 and between the top and bottom members 1 and 2 are the impression dies 6 and 7, the die 6 being secured to the bottom section 2 of the casing while the die 7 is carried by a leaf-spring 8, which normally presses the same upwardly from the die 6 in order that these members normally will be held in separated relation unless forced together 55 to form an impression. The spring 8 is shown

as having one end attached to the impression die 7, while the other end is riveted to the lower section 2, but the shape of this spring may be varied as desired, so long as it normally tends to separate the impression dies.

The die 7 has a semi-rounded projection 9 on the upper side thereof in alignment with a rounded projection 10 formed in the top section 1 of the casing, which projections 9 and 10 normally are in contact by reason of the pressure of the spring 8. A lever 11 is pivoted on the bolt 12, which passes through the sections of the casing and has a cam notch 13 in one end thereof, in position to be pressed between the projections 9 and 10, whereby to force the impression die 7, downward against the impression die 6 and form the impression therebetween. The top and bottom surfaces of the lever 11, adjacent the notch cam 13 are flat, so as to force the projections 9 and 10 apart, while the lever 11 is moved in one direction by its handle portion 14. A spring 15 may be used to return the lever 11 to its normal position.

In order to form the impression, it is only necessary to insert a paper into the mouth 5 between the impression dies 6 and 7, and press backward on the handle 14 in the direction of the arrow in Fig. 1, which forces the opposite end of the lever 11, having the notch cam 13, between the projections 9 and 10, spreading these and forcing the die 7 downward with sufficient pressure to form the impression in the paper between the dies 6 and 7. 25 30

Instead of having the notch cam 13 formed on an end of the lever 11, it may be formed as a separate cam indicated at 23, on Fig. 5, pivotally supported by the top section 1 of the casing as at 24 and connected with the handle 25, by means of a link 28. The handle 25 is pivoted as at 26 so that when it is swung about said pivot, the link 28 is moved lengthwise to turn the cam 23, about its pivot 24, and thereby move the impression die 21 downward to form the impression. 35 40

If desired, the hand lever 35 may operate the cam segment 31, pivoted at 38 to one of the sections of the casing, by means of rack teeth, shown at 36 in Fig. 6, in order to swing the cam segment to cause relative movement between the impression dies. 45

I claim:

1. In an impression seal, the combination of an impression die movable toward and from the cooperating surface and having a rounded projection thereon, a cam member arranged for wedging movement in a plane extending trans-

versely of the direction of movement of the die for engaging said rounded projection to move the die, and means for operating said cam member.

2. In an impression seal, the combination of a pair of impression discs mounted for relative movement therebetween, one of said discs having a rounded projection thereon, a cam arranged for wedging movement in a plane approximately at right angles to the direction of relative movement of the discs and in position to engage the rounded projection for causing said relative movement of the discs, and means for operating said cam.

3. In an impression seal, the combination of a pair of impression dies, one of which is movable relative to the other, said movable die having a projection thereon, a casing having a projection in alignment with the projection on the die, and wedging means in position to be forced between said projections to cause movement of the movable die.

4. In an impression seal, the combination of a pair of impression dies, one of which is movable toward and from the other, said movable die having a rounded projection thereon, a casing for the seal having a rounded projection extending in the direction of the first-mentioned rounded projection and in alignment therewith, and wedging means arranged for movement between said projections to cause movement of the movable die toward the other.

5. In an impression seal, the combination of a relatively flat elongated casing constructed of sheet metal and having a mouth at one end thereof with its width arranged in the plane of the greatest width of said casing, impression dies arranged in said mouth for relative movement, and

means extending in said casing and extended at the opposite end thereof from said mouth for causing relative movement between the dies.

6. In an impression seal, the combination of a casing constructed of sheet metal in substantially flat elongated shape and having a mouth at one end thereof arranged in the plane of the greatest width of said casing, impression dies in said mouth mounted for relative movement therebetween, and means for operating said dies and extending in the casing and movable in a plane extending parallel with the greatest width of the casing.

7. In an impression seal, the combination of a casing constructed of sheet metal in substantially flat elongated shape and having a mouth at one end thereof arranged in the plane of the greatest width of said casing, impression dies in said mouth mounted for relative movement, one of said dies having a rounded projection thereon, the casing having a rounded projection in alignment with the first-mentioned projection, and a lever pivotally mounted in the casing and movable in the plane of greatest width of the casing, and having an end portion arranged for wedging movement between the projections.

8. In an impression seal, the combination of a casing having a pair of impression dies, one of which is movable relative to the other and having a rounded projection centrally arranged thereon, the casing having a projection in alignment with the first-mentioned projection, and a lever pivotally mounted in the casing and having an end portion arranged for wedging movement between the projections.
